UNITED STATES PATENT OFFICE

155,835

DESIGN FOR A REARVIEW MIRROR

Frank C. Perry, Detroit, Mich., assignor to Monarch Governor Company, Detroit, Mich., a corporation of Michigan

Application February 20, 1948, Serial No. 144,647

Term of patent 7 years

(Cl. D14—6)

To all whom it may concern:

Be it known that I, Frank C. Perry, a citizen of the United States, residing at Detroit, county of Wayne, State of Michigan, have invented a new, original, and ornamental Design for a Rearview Mirror, of which the following is a specification, reference being had therein to the accompanying drawings, forming a part thereof, in which

Fig. 1 is a plan view of a rearview mirror, illustrating my new design.

Fig. 2 is a side elevation thereof.

Fig. 3 is an end view.

The dominant features of my new design reside in the portions shown in full lines.

I claim:

The ornamental design for a rearview mirror, substantially as shown and described.

FRANK C. PERRY.
